UNDERGROUND SHELTER
Ahmed Jaha, Stanley, N. Dak.
Filed May 18, 1962, Ser. No. 195,831
2 Claims. (Cl. 98—33)

This invention relates to new and useful improvements in underground shelters and has for its primary object to provide, in a manner as hereinafter set forth, a reinforced masonry structure of this character which is capable of 10 withstanding nuclear bombings and protecting its occupants therefrom and from subsequent fall-out for a considerable length of time.

Another highly important object of the present invention is to provide an improved shelter of the aforementioned character comprising a novel ventilating system for ensuring an adequate supply of fresh, filtered air for 15 as long as it may be needed.

Still another important object of the invention is to provide a ventilated nuclear bomb shelter of the character described to which access is had from the basement of an immediately adjacent or adjoining house or other building.

Other objects are to provide an underground shelter of the character set forth which is of comparatively simple 25 construction, strong, durable, fireproof, comfortable and which may be constructed at low cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a vertical sectional view through a shelter constructed in accordance with the present invention, taken substantially on the line 1—1 of FIGURE 2;

FIGURE 2 is a view in horizontal section through the shelter;

FIGURE 3 is a vertical sectional view through the intake air duct, taken substantially on the line 3—3 of 40 FIGURE 1;

FIGURE 4 is a vertical sectional view through the exhaust air duct and the adjacent portion of the roof structure, taken substantially on the line 4—4 of FIGURE 1;

FIGURE 5 is a vertical sectional view through the manual air suction fan;

FIGURE 6 is a view in transverse section through the fan, taken substantially on the line 6—6 of FIGURE 5; and

FIGURE 7 is a view in horizontal section on an enlarged scale through the air filter, taken substantially on the line 7—7 of FIGURE 3.

Referring now to the drawing in detail, it will be seen that reference numeral 8 designates generally the masonry basement of a house or other building. The basement 8 includes a concrete foundation wall 9 rising from a floor 10, said wall 9 having an opening or passage 11 therein.

The shelter of the present invention comprises a reinforced concrete floor 12 of suitable dimensions. As shown to advantage in FIGURE 1 of the drawing, the floor slab 12 is poured below the level of the floor 10. The upper surface of the floor 12 slopes to a drain 13 which may discharge into a suitable gravel well 14 or the like beneath said floor. Reference numeral 15 indicates a footing for the floor 12. If desired, the slab or floor 12 may include a suitable finish floor. Where necessary, the floor 12 may be poured on a suitable plastic sealing film.

Rising from the floor 12 are front, rear or back and

2

side walls 16, 17 and 18, respectively. The wall 16 has an elevated opening or passage 19 therein aligned with the opening or passage 11. Thus, the shelter is communicated with the basement 8. A suitable fire door 20 is provided in the opening 19. Steps 21 are provided from the floor 12 to the opening 19.

Mounted on the walls 16, 17 and 18 is a concrete roof 22. The roof 22 is covered to the desired depth with a fill 23 of earth or other suitable material. The roof 22 is strengthened by crossed reinforcing rods 24. The end portions 25 of the rods 24 extend downwardly into the walls 16, 17 and 18 for tying said walls and the roof 22 together. Above the reinforcing rods 24, the roof 22 is further strengthened by a reinforcing mesh 26. The roof 22 is tied or anchored to the basement wall 9 at 27.

A vertical air intake pipe 28 extends through the roof 22 and fill 23 to a point above the surface of the ground and terminates at its upper end in a T-head 29 comprising downturned screened end portions 30. The air intake pipe 28 is positively anchored at 31 in the roof 22. The pipe 28 extends downwardly adjacent the rear wall 17 to a point adjacent to but spaced above the floor 12 and the lower or outlet end of said pipe is provided with a removable cap 32 the loss of which is prevented by a chain 33. Interposed in the air intake pipe 28, adjacent the roof 22 is a filter cartridge or unit 34. The cartridge or unit 34 is readily removable for replacement and a hinged door 35 provides access thereto.

Projecting horizontally from the lower portion of the air intake pipe 28 is an outlet branch 36. A manually actuated suction fan 37 is provided on the discharge end of the branch 36.

Also extending through the roof 22, adjacent the front wall 16, is a relatively short air outlet or exhaust pipe 38. The exhaust pipe 38 is anchored at 39 in the roof 22. The lower end of the pipe 38 is flush with the under-surface of the roof 22. The upper end portion of the exhaust pipe 38 is substantially similar to that of the intake pipe 28, comprising a T-head 40 which terminates in downturned screened end portions 41.

It is thought that the use or operation of the shelter will be readily apparent from a consideration of the foregoing. Of course, when an alarm is received the shelter is entered through the aligned passages 11 and 19 past the fire door 20. Reference numeral 42 designates a baffle wall in the shelter in front of the fire door 20. When the shelter is in use warm air therein rises in the usual manner and passes to the atmosphere through the outlet or exhaust pipe 38. Thus, with the cap 32 removed, fresh air from the atmosphere is drawn downwardly through the inlet pipe 28 into the shelter, said incoming air passing through the filter 34. Or, if desired, the cap 32 may be applied to the lower end of the pipe 28 and the suction fan 37 may then be actuated for drawing air through the pipe 28 into the shelter. When the air from the atmosphere is thus drawn by force into the shelter the air in said shelter is ejected therefrom through the discharge pipe 38. In the installation shown, a tongue and groove joint 43 is provided between the shelter floor 12 and the upstanding walls 16, 17 and 18. This joint may be further sealed in any suitable manner at 44. The baffle wall 42 will shield occupants of the shelter from any direct blast through the openings 11 and 19. Of course, the enclosure or shelter, which may be of various dimensions, is to be suitably equipped and supplied for occupancy by one or more persons.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and

equivalents may be resorted to, falling within the scope of the invention as claimed.

What is claimed as new is as follows:

1. In combination, a building structure embodying a basement having a floor and at least one vertical wall, said vertical wall being provided with an escape opening, an underground fallout shelter cooperable with said basement wall and comprising a floor, front, rear and side walls and a roof cooperating with said walls, said front wall abutting the vertical wall of said basement and having an entrance and exit doorway therein in communication with said escape opening, said doorway being provided with a fire door, a vertical baffle wall marginally joined to the floor, roof and one side wall and spaced from said doorway and having one vertical edge spaced from an interior surface of the other side wall and permitting occupants to gain access to said shelter, the level of said floor being in a plane below the level of the basement floor and that portion of the shelter and floor thereof which is adjacent to and in alignment with said doorway being provided with steps, and ventilating means for the interior of said shelter comprising an atmospheric air intake and supply conduit extending from a point above ground level and vertically downward through said roof and into the interior of said shelter, an air exhaust conduit extending through the roof and affording communication between the interior of said shelter and the atmosphere, the upper end of said exhaust pipe likewise extending to a level above the ground, the upper end of each conduit having an integrally mounted tubular horizontal crosshead communicatively connected to said upper end, the respective outward ends of said crosshead having downturned screen-covered end portions, an air suction fan communicatively connected to said air intake conduit and adapted to deliver atmospheric air therethrough into the interior of said shelter, a readily insertable and removable filter cartridge fitted through an opening provided therefor in said intake conduit, and a door hingedly mounted on said conduit and normally closing said opening and affording access to said cartridge, said opening, door and cartridge being disposed in a plane above the plane of said suction fan.

2. In combination, a building structure embodying a basement having a floor and at least one vertical wall, said vertical wall being provided with an escape opening, an underground fallout shelter cooperable with said
